GARMENT RACK

Raymond A. Magnuson, Hinsdale, and Robert W. Schier, Northbrook, Ill., assignors to Vogel-Peterson Co., Chicago, Ill., a corporation of Illinois

Filed June 15, 1965, Ser. No. 85,746

Term of patent 14 years

(Cl. D33—8)

The figure is a perspective view of a garment rack embodying our new design.

We claim:

The ornamental design for a garment rack, substantially as shown.
